FLUID DISCHARGE GUN

Winthrop R. Stone, Winfield, W. Va., assignor to Union Carbide Corporation, a corporation of New York
Filed Apr. 12, 1961, Ser. No. 102,595
4 Claims. (Cl. 239—107)

The present invention relates to a fluid discharge gun for spray-feeding of fluids and more particularly to a gun for feeding a wide variety of waste products into a furnace for disposal by burning. The materials that can be successfully handled may be of variable viscosity and composition, contain flocculated or granular particles and be highly corrosive or erosive in nature.

Many industrial processes produce by-product waste materials which are difficult of disposal since they vary in composition, consistency and in viscosity. Known waste burner guns which are adapted to handle a particular waste substance efficiently are found to malfunction when other substances are introduced to the waste stream. Not infrequently, waste product streams are found to contain foreign matter such as wood splinters, fibers and metallic and organic scales which tend to clog ports and orifices of known burner guns. Since waste materials derive from points at varying process pressures, and from different types of pumps, according to particular systems, steady pressure cannot be maintained at the burner gun. Known guns have been found to operate inefficiently under varying input pressure. Waste materials which are corrosive or erosive, or both, react with and cause severe wear on known burner guns, necessitating their frequent replacement. Known burner guns have also been found occasionally to heat to excess, causing the coking of certain residue materials inside the gun and sometimes burning of the gun itself.

The apparatus of the present invention comprises a unique residue burning gun which offers outstanding advantages over known burner guns in versatility, reliability, long life, ease of maintenance, and operating characteristics. The residue burning gun of the present invention provides for crushing of solid particles in the waste feed stream, adjusts to constant furnace feed rates for a wide variety of upstream pumping apparatus over a wide pressure range, regardless of the viscosity or composition of the feed, and is self-adjusting and self-cleaning. The gun is also adapted for the easy replacement of high-wear components, obviating the necessity of replacing the entire apparatus because of worn individual parts. Due to the use of especially hard materials at critical wear points, the gun has an extraordinarily long operating life even when used with highly abrasive materials such as sand and the like. The gun is also provided with a water jacket to cool the gun and feed stream and prevent burning the gun or coking of waste materials in the feed stream. When used with corrosive materials, the design of the apparatus of the present invention permits the use of materials of construction capable of withstanding the corrosion of internal parts without requiring the use of such materials for body portions of the apparatus.

In general, the apparatus of my invention comprises a fixed generally cylindrical hollow body portion, or barrel, adapted for mounting in a furnace wall, with a fuel inlet end exterior of the furnace and a nozzle end interior of the furnace. An elongate stem is concentrically disposed and resiliently suspended in the body portion and moves reciprocally therein, according to gun body internal pressure working against bias exerted by a resilient means connecting the body and the stem. An orifice of variable cross-section is defined at the nozzle end of the gun between matching surface portions of the body and the stem. For the reduction of solids occurring in the fluid stream, the gun includes comminuting means, said comminuting

2

means comprising components affixed to the body and stem portions of the gun.

With the foregoing and other features in view, which shall more fully hereinafter appear, the invention comprises novel constructions, combinations and arrangements of components as will now be described and as defined in the appended claims and as illustrated in preferred embodiment in the accompanying drawings, wherein:

FIGURE 1 is an elevational longitudinal sectional view of the residue burning gun of the present invention;

FIGURE 2 is a cross sectional view through a point adjacent the nozzle end of the gun of FIGURE 1 showing the concentric arrangement of component parts at that point and

FIGURE 3 is a cross sectional view through a point adjacent the coolant ports showing the concentric arrangement of component parts at that point and the arrangement of the coolant baffles.

In an embodiment of the apparatus of the present invention according to the drawings, a cylindrical body 11 of the gun is shown provided with a coolant inlet 15 and a coolant outlet 17. A pair of longitudinally extending baffles 12 and 14 divides chamber 13 into two end-connected flow paths to assure full length travel of the coolant. One end of the body 11, which end shall for convenience be called the nozzle end, is formed to define a radial intrusion 19 bounded by a short axially extending annular wall 21 and by axially and radially extending walls 23 and 25. The other end of body 11 is formed to define a bolting flange 27. A gun head assembly 29, having a bolting flange 31, which matches flange 27, includes a packing gland 33, a packing follower 35, a spring seat base 37 and an adjustable spring seat 39 threadedly engaged in the base 37 and having an axially extending center bore therethrough.

A reciprocally movable stem assembly which shall be more completely described below, extends through the gun body and gun head assembly and is held in coaxial alignment therewith by means of sliding contact with bearing liner 49, a centerbore in the flange portion of head assembly 29, the packing follower 35 and the centerbore of spring seat 39. A coil spring 65 is installed, biased compressively, between spring seat 39 on the gun head assembly and a spring seat component on the stem assembly in a manner which tends to close the nozzle end of the gun.

To assemble the gun according to the drawing, a gasket 41, an annular seat ring 43 and a gasket 45 are inserted into body 11 from the flanged end and are positioned against wall 23 of radial intrusion 19. A sleeve bearing 47 with a bearing liner 49 is next inserted from the body 11 flanged end. Bearing liner 49 is provided with an axially extending annular protrusion having an outer periphery which engages the inner circumferential wall of seat ring 43 in a close fit to concentrically align the several parts. A backing plate 51 is next inserted to fit behind the sleeve bearing and bearing liner. The rearwardly projecting portion of backing plate 51, i.e., the face away from the nozzle end of the gun body, is provided with a male hub which engages an interior wall of one end of a gun liner sleeve 53, which liner sleeve extends coaxially inside gun body 11, defining a small annular space between its outer peripheral wall and the inner wall of body 11. The other end of the liner sleeve 53 is supported and aligned by a male hub on a threaded sleeve retainer 55 which screws into threads in the flange end of the gun body 11. Sleeve retainer 55 is provided with a relatively large axially extending opening 56 which, in the embodiment shown, is shaped to accommodate a square-ended wrench to facilitate assembly. In some instances it may be found desirable to fill the annular space between the liner sleeve 53 and the gun

body interior wall with a non-congealing lubricating compound which can facilitate disassembly of the gun.

A breech 57, provided with a fuel or residue entry port 59 is mounted between the flanges 27 and 31, which are provided with facia recesses to accommodate the breech ends. Gaskets 61 are installed in the flange facia recesses to effect sealing and the assembly is secured by a circumferential array of bolts 63.

The movable stem portion of the gun is comprised mainly of a relatively thin hollow cylindrical stem piston 67 having a radially enlarged head 69 of a circumference greater than the inner circumference of radial intrusion 19 at the nozzle end of the gun body. Stem head 69 is provided with a rearwardly extending (i.e., to the left in the drawing) relatively sharp annular projection defined by the respective axially and radially extending surfaces 71 and 73. The movable stem portion of the gun is assembled by first arranging a gasket 75, a valve disc 77 and a gasket 79 in the recess under stem head 69 defined by surface 71 and the end of stem piston 67. A fluted ferrule 81, having a multiplicity of axially extending circumferentially spaced flutes 83, is assembled behind gasket 79. Ferrule 81 is essentially a hollow cylinder having an inside diameter to fit slidably over stem piston 67 and an outside diameter to fit slidably inside liner 49 of sleeve bearing 47, seat ring 43 and backing plate 51. The flutes 83 in ferrule 81 can be milled or otherwise formed in the peripheral surface of the ferrule and extend for slightly less than the ferrule full length.

In the preferred embodiment of apparatus according to my invention, the flute depths are diminished to meet the outer circumference of the ferrule at the ferrule end faces. A gasket 85 and a locking nut 87 are then installed to complete the stem assembly at the nozzle end of the gun.

The partially assembled stem portion is then inserted, thin end first, through the nozzle end of gun body 11, seat ring 43, bearing liner 49, backing plate 51, liner sleeve 53, opening 56 in retainer 55, breech 57, the centerbore in flange 31 of the head assembly, packing 33, packing follower 35 and the centerbore of spring seat 39.

Coil spring 65 is then installed over the end of stem piston 67 projecting from spring seat 39 and spring seat 39 is assembled over the spring and stem piston. A cylindrical headpiece 91, which is a combination coolant connector and assembly lock nut is axially centerbored and threaded to screw onto threads on the projecting end of piston stem 67. Headpiece 91 is also provided with a tapped counterbore concentric with the centerbore, into which counterbore is screwed a long relatively thin coolant conduit 93 which extends from the headpiece 91 through stem piston 67 to a point just opposite the interior wall of stem head 69. In the preferred embodiment, this interior wall is provided with a conically projecting flow divider 95 arranged in the flow path of coolant emerging from the nozzle end of coolant conduit 93. Coolant inlet 97 which connects to the tapped counterbore and coolant outlet 99 which connects to the interior of stem piston 67, are also provided in headpiece 91.

In operation, any suitable coolant, such as water, is introduced under pressure through coolant inlet 97 to conduit 93 from which it emerges in piston head 69 opposite flow divider 95, fills the cooling chamber in the piston head, flows back through the annular space defined by the outer surface of conduit 93 and the inner wall of stem piston 67 and discharges through coolant outlet 99. Coolant is also supplied to the body portion of the gun through inlet 15 whence it flows through a first half-annular portion of cooling chamber 13 to the nozzle end of the gun, around the baffle ends and back through a second half-annular portion of chamber 13 to the coolant outlet 17. The type of coolant used, the pressure, flow rate, temperature control, recirculation systems and other matters of concern in cooling will vary depending on the particular applications and environ-

ments in which the apparatus of my invention is used. Here it should be noted that, since headpiece 91 is reciprocally movable along with the movable stem portion of the gun, cooling system connections are best made thereto by means of flexible conduits.

The gun is mounted in a furnace wall with the nozzle end projecting into a combustion chamber. Conduit containing the fluid to be introduced into the furnace through the gun, is connected to the breech at fluid entry port 59. Under pressure of the fluid system, the fluid fills the breech, flows through the opening in sleeve retainer 55 into the annular space defined by the inner wall of liner sleeve 53 and the outer surface of stem piston 67, through the flutes 83 in ferrule 81 and out of the nozzle end of the gun through the frusto-conical aperture defined between the parallel axially and radially extending surfaces of seat ring 43 and valve disc 77. Here it should be noted that this aperture is in effect an automatic nozzle port for the gun. Spring 65 is compressed by adjustment of spring seat 39 to a bias which effects full closure of the aperture between seat ring 43 and valve disc 77 up to a preselected fluid pressure and then a gradual opening of the aperture according to pressure of the fluid system.

Solid particles such as wood fibers and organic granular material collect at the nozzle aperture. When they build up or agglomerate sufficiently to attenuate the discharge, backpressure builds up in the gun, causing the stem piston to move, opening the aperture wider and permitting discharge of the obstructing material into the combustion zone of the furnace. After each such occurrence, the return of the valve disc to its original position with respect to seat ring 43 is automatically accomplished by the biased spring 65.

The reciprocal movement of the stem portion of the gun also causes relative movement of fluted ferrule 81 with respect to the several parts within which it is arranged. This action not only has a comminuting effect on most contaminant particles but also prevents clogging by particles too hard to be comminuted. Some comminution also takes place in the nozzle aperture itself due to the relative movement of the aperture walls defined by the parallel-extending opposed surfaces on seat ring 43 and valve disc 77. Thus, it will be seen that the apparatus of the present invention comprises a residue burning gun which not only comminutes most contaminant particles occurring in the feed fuel stream, but which also adjusts to discharge particles which cannot be effectively comminuted during passage through the gun. Fluted ferrule 81 sliding in backing plate 51 and bearing liner 49 with a close clearance acts to crush and shear any oversized granular or fibrous solid particles entering the flutes 83. This automatic reduction of solids greatly reduces the fouling tendency at the discharge nozzle of the gun and makes for smoother operation.

With the foregoing description in mind, mechanically skilled persons can readily select suitable materials of construction and can adapt the apparatus of my invention to particular applications. It will be apparent from the description that the parts of the apparatus which are most subject to corrosive or erosive attrition such as gun liner sleeve 53, bearing liner 49, ferrule 81, seat ring 43, valve disc 77 and similarly related parts are readily replaceable, obviating the need to replace main body portions of the gun. This design feature also permits the use of materials of construction able to withstand corrosion and erosion without requiring the use of such relatively expensive materials for body portions of the device.

In a particular embodiment of apparatus according to the present invention, a residue burning gun was designed and constructed to inject waste fluids from hydrocarbon production processes into an industrial power plant boiler, under pressures of from 400 p.s.i.g. to 600 p.s.i.g. Bearing liner 49, ferrule 81, backing plate 51, gun liner sleeve 53, and the stem head 69 are fabricated from stainless

steel. Valve disc 77 and seat ring 43 are made from tungsten carbide, all gaskets are of soft aluminum and body 11, head assembly 29 and other parts were of mild steel.

This gun was installed where several standard commercially available residue burning guns had previously been used with less than satisfactory results. Prior to the installation of the apparatus of the present invention, malfunctioning due to clogging and plugging of known apparatus occurred continually at periods of from one hour or less up to maximum operating times of six to eight hours. Routine cessation of residue waste feeding and removal and cleaning of the then used apparatus was required. Excessive abrasion and corrosion occurred on these guns when kept in this service for only short periods of time. Some of the known guns employed required steam or air service connections for atomizing the fluid residues. It was also found that, even when these known guns were running unclogged, there was considerable difficulty in maintaining feed rate control. Waste type residue feed streams comprise portions which are thin and watery, portions of varying viscosity emulsions and portions of heavy, tarry fluid, all interspersed with fibrous and granular solid contaminants. Thus, the tendency of standard commercially available guns is to feed too much thin watery residue, too little of heavy emulsion or tarry components and to clog and shut off completely when solid contaminants such as wood fiber occur in the feed stream.

After the installation of apparatus according to the present invention in place where a standard commercially available burner gun had been used, the apparatus of the present invention operated continually for a period of approximately nine months without malfunction and with no down time occurring due to either plugging or mechanical failure. During this nine month period approximately 2,000,000 pounds of hydrocarbon production process waste residues, along with varying small amounts of other residues, were processed through the gun. At the end of this period of duty, the gun was taken out of service, dismantled and inspected to determine the conditions of internal parts. It was found that all of the internal parts were in good condition. The bottom surfaces of the inlet ends of the flutes 83 on ferrule 81 were found to be slightly eroded. This component, since it is formed symmetrically, was turned around upon reassembly to present new wearing surfaces to the flow stream. It should be noted here that fluted ferrule 81 is one of those parts expected to wear and be replaced as occasion requires. The tungsten carbide seat ring 43 and valve disc 77 showed so little evidence of wear as to not even require refacing or grinding.

Since many changes could be made in the specific combinations of apparatus here disclosed and many apparently different embodiments of this invention can be made without departing from the scope thereof, it is intended that all matter contained in the foregoing description and shown in the accompanying drawing shall be interpreted as being illustrative and not in a limiting sense.

What is claimed is:

1. A fluid residue burning gun comprising, in combination, a fixed generally cylindrical hollow body portion and a stem portion concentrically disposed with respect to said body portion to define a fluid passage terminating in a variable size fluid discharge aperture, fluid inlet means connecting to said passage adapted for connection to a conduit containing pressurized fluid to be discharged through the gun, resilient means connecting said body portion and said stem portion adapted to exert a preselected resilient bias on said stem portion in a direction opposite

fluid pressure-induced movement of said stem, said direction being a direction of movement tending to close the fluid discharge aperture and coolant passages disposed in said body portion and in said stem portion, adapted for connection to circulating coolant cooling systems.

5 2. Apparatus according to claim 1 in combination with comminuting means adapted for the reduction of solids occurring in fluids discharged through the gun, said comminuting means comprising a first component affixed to the body portion of the gun and a second component affixed to the stem portion of the gun.

10 3. Apparatus according to claim 1 in combination with replaceable first comminuting means adapted for continual compressive reduction of solids occurring in fluids 15 discharged through the gun, said first comminuting means comprising two generally conical and substantially matching surfaces, one of said surfaces being on a component affixed to the body portion of the gun and the other of said surfaces being on a component affixed to the stem portion of the gun and replaceable second comminuting means adapted for continual shearing reduction of solids occurring in fluids discharged through the gun, said second comminuting means comprising a hollow cylindrical liner arranged and disposed longitudinally in the fixed portion 20 of the gun and a cylindrical longitudinally surface fluted ferrule on the stem portion of the gun arranged to move reciprocally in the hollow cylindrical liner.

25 4. A fluid discharge gun comprising, in combination, a fixed generally cylindrical hollow body portion, a stem portion arranged longitudinally and concentrically with respect to said body portion to define a fluid passage terminating in a variable size fluid discharge aperture having a frusto conical shape, fluid inlet means connecting to said fluid passage adapted for connection to a conduit containing pressurized fluid to be discharged through the gun, resilient means connecting said body portion and said stem portion arranged and disposed to exert a preselected resilient bias on said stem portion in a direction opposite 30 fluid pressure-induced movement of said stem, said direction being a direction of movement tending to close the fluid discharge aperture, first comminuting means adapted for continual compressive reduction of solids occurring in fluids discharged through the gun, said first comminuting means comprising two generally conical and substantially matching surfaces, one of said surfaces being on a component affixed to the body portion of the gun and the other of said surfaces being on a component affixed to the stem portion of the gun and replaceable second comminuting means adapted for continual shearing reduction 35 of solids occurring in fluids discharged through the gun, said second comminuting means comprising a hollow cylindrical liner arranged and disposed longitudinally in the fixed portion of the gun and a cylindrical longitudinally surface fluted ferrule on the stem portion of the gun arranged to move reciprocally in the hollow cylindrical liner.
